[57] CLAIM

The ornamental design for a cup, as shown and described.

DESCRIPTION

FIG. 1 is a perspective view of the cup design of the present invention;

FIG. 2 is an elevational view;

FIG. 3 is an elevational view taken 90 degrees from the elevational view of FIG. 2;

FIG. 4 is an elevational view taken 180 degrees from the view of FIG. 3;

FIG. 5 is an elevational view taken 180 degrees from the view of FIG. 2;

FIG. 6 is a top plan view;

FIG. 7 is a bottom plan view;

FIG. 8 is a perspective view of another embodiment of the design of the present invention;

FIG. 9 is an elevational view of the embodiment of FIG. 8;

FIG. 10 is an elevational view taken 90 degrees from the elevational view of FIG. 9;

FIG. 11 is an elevational view taken 180 degrees from the elevational view of FIG. 10;

FIG. 12 is an elevational view taken 180 degrees from the elevational view of FIG. 9;

FIG. 13 is a top plan view of the embodiment of FIG. 8;

FIG. 14 is a bottom plan view of the embodiment of FIG. 8;

FIG. 15 is a perspective view of another embodiment of the design of the present invention;

FIG. 16 is an elevational view of the embodiment of FIG. 15;

FIG. 17 is an elevational view taken 180 degrees from the elevational view of FIG. 16;

FIG. 18 is an elevational view taken 90 degrees from the elevational view of FIG. 17;

FIG. 19 is an elevational view taken 180 degrees from the elevational view of FIG. 18;

FIG. 20 is a top plan view of the embodiment of FIG. 15;

FIG. 21 is a bottom plan view of the embodiment of FIG. 15;

FIG. 22 is a perspective view of another embodiment of the design of the present invention;

FIG. 23 is an elevational view of the embodiment of FIG. 22;
FIG. 24 is an elevational view taken 180 degrees from the elevational view of FIG. 23;
FIG. 25 is an elevational view taken 90 degrees from the elevational view of FIG. 23;
FIG. 26 is an elevational view taken 180 degrees from the elevational view of FIG. 25;
FIG. 27 is a top plan view of the embodiment of FIG. 22;
FIG. 28 is a bottom plan view of the embodiment of FIG. 22;
FIG. 29 is a perspective view of another embodiment of the design of the present invention;
FIG. 30 is an elevational view of the embodiment of FIG. 27;
FIG. 31 is an elevational view taken 90 degrees from the elevational view of FIG. 30;
FIG. 32 is an elevational view taken 180 degrees from the elevational view of FIG. 30;
FIG. 33 is an elevational view taken 180 degrees from the elevational view of FIG. 31;

FIG. 34 is a top plan view of the embodiment of FIG. 29;
FIG. 35 is a bottom plan view of the embodiment of FIG. 29;
FIG. 36 is a perspective view of another embodiment of the design of the present invention;
FIG. 37 is an elevational view of the embodiment of FIG. 36;
FIG. 38 is an elevational view taken 180 degrees from the elevational view of FIG. 37;
FIG. 39 is an elevational view taken 90 degrees from the elevational view of FIG. 37;
FIG. 40 is an elevational view taken 180 degrees from the elevational view of FIG. 39;
FIG. 41 is a top plan view of the embodiment of FIG. 36; and,
FIG. 42 is a bottom plan view of the embodiment of FIG. 36.
